(57) **ABSTRACT**

The air cells are attached detachably to the base members. By this, it is possible to set up the size or the arrangement of the air cells. For example, in a hospital, it is possible to change easily and inexpensively the air cells on a bed according to the patient's height, the body shape, the state, or the condition of affected part. Thus, it is exceedingly advantageous for dispersing the pressure added to the body.

AIR CELL UNIT AND CUSHION

BACKGROUND OF THE INVENTION

(i) Field of the Invention

The present invention relates to, for example, an air cell unit and cushion which is having a plurality of air cells disposed in some flat direction on a bed of a hospital or on a wheelchair and which is used for preventing occurrence of a bedsore on a patient.

(ii) Description of the Related Art

A generally known cushion comprises a plurality of air cells disposed in some flat direction and being capable of housing air respectively, and a ventilation passage for connecting the interiors of the air cells each other and equalizing the air pressures in the air cells. Said cushion disperses the pressure being exerted on the body on the air cells and prevents occurrence of a bedsore.

By the way, above mentioned cushion with air cells is composed of a upper sheet-like member formed integrally with a plurality of air cells and a bottom sheet-like member having area equivalent to the upper sheet-like member. The upper sheet-like member has the area according to the size of the bed and is made from flexible material such as rubber material or resin material. The bottom sheet-like member is pasted to the undersurface of the upper sheet-like member, and the opening portion of each air cell bottom is closed by the bottom sheet-like member. Also, the ventilation passage for making the insides of the air cells communicate each other is disposed between those sheet-like members.

In this case, it is desirable to respectively set up the size and the arrangement of the air cells according to the patient's height, body shape, or the state and condition of the affected part in order to disperse more effectively the pressure being added to the body.

However, in the above-mentioned cushion, it is necessary to change the shape of a upper sheet-like member in order to change the size and arrangement of air cells. Also, since the air cells of the upper sheet-like member are molded by a plurality of concave portions or convex portions of the metallic mold, a plurality of metallic molds are needed according to the number of the kind of upper sheet-like member. Namely, it is impossible to change the size and arrangement of the air cells according to the patient's height, body shape, or the state and condition of the affected part.

Also, in order to disperse the pressure added to the body, it is desirable that air cells are flexible. However, the flexible air cell tends to generate an air leak by breakage. Also, since air cells communicate with each other by a ventilation passage, other non-breakage air cells are influenced by breakage of some air cells. Therefore, when the air cell is damaged, it is necessary to perform repair of a breakage part, or exchange the cushion itself. By this, in repair of a breakage part, time and effort is taken, and when it is the exchange of the cushion itself, expense costs dearly.

Moreover, in order to keep air cells always clean, it is desirable to use respectively a new cushion for every patient in a hospital. However, since much expense is needed to purchase cushions for every patient respectively, under the present circumstances, the cushion is washed and used repeatedly. In this case, the air cells are flexible and breakable, and it is difficult to wash a plurality of air cells being disposed each other. By this, it is impossible to wash the air cells fully.

size of the air cells or the arrangement of the air cells, repairable easily and inexpensively at the time of breakage of the air cell, and capable of keeping the air cells clean always.

In order to achieve the above object, in the present invention, a cushion is provided with a plurality of air cells formed to a bag-like shape and being capable of housing air, the air cells having at least one opening portion respectively and having flexibility, a plurality of protrusion portions arranged in a certain plane surface direction, the protrusion portion 10 having an outer surface to which a opening end part of the air cell is detachably attached by fitting so that the air cells are arranged in the certain plane surface direction, a air passage for sucking/exhausting air in the air cells, which are being attached to the protrusion portions, via the opening portions 15 of the air cells.

Thus, by using two or more kinds of the air cells from which a size differs, it is possible to set up arbitrarily sizes of air cells which are provided so as to be disposed in the certain plane surface direction. By this, for example at a hospital, it is 20 possible to change the size of the air cells easily and inexpensively according to the patient's height, body shape, or the state and condition of the affected part. It is exceedingly advantageous for dispersing effectively the pressure added on a patient's body.

Moreover, the air cells are being attached to the protrusion portions detachably. By this, when breakage arises on some air cells among the air cells, it is possible to change only the broken air cells. Thus, it is possible to repair the air cells easily and inexpensively.

Also, the air cells are being attached to the protrusion portions detachably. By this, it is possible to remove each air cell and to wash each air cell respectively, and it is possible to exchange some air cells for new air cells. By this, for example at a hospital, washing of the air cells becomes easy, and it is 30 possible to exchange some air cells for new air cells according to the state of the air cells. Thus, it is exceedingly advantageous for keeping the air cells clean always.

In order to achieve the above object, in the present invention, a air cell unit is provided with an air cell formed to a bag-like shape and being capable of housing air, the air cell having at least one opening portion and having flexibility, a base member having a board-like shape, a protrusion portion provided on one thickness-direction surface of the base member so as to protrude from one thickness-direction surface of 40 the base member, the protrusion portion having outer surface on which a opening end part of the air cell is detachably attached by fitting, a projection portion and/or recessed portion provided on an end portion in the direction perpendicular to the thickness direction of the base member, the projection portion and/or a recessed portion for connecting the base member and another base member by being formed so as to connect with the projection portion and/or the recessed portion of another base member when the base member and another base member are disposed on a flat direction so that 45 their end portions in the direction perpendicular to the thickness direction come close each other, and a air passage provided in the base member, the air passage for sucking/exhausting air in the air cell which is being attached to the base member via the opening portion, the air passage capable of connecting with the air passage of another base member.

Thus, the base member is connected with another base member and disposed on some flat surface. Also, the air cell is detachably attached to each base member respectively. The air passages of the base members are capable of communicating each other. By this, it is possible to dispose a plurality of air cells in some flat direction and make the insides of the air cells connect each other.

SUMMARY OF THE INVENTION

An object of the present invention is to provide an air cell unit and cushion changable easily and inexpensively in the

At this time, arrangement of the air cells can be arbitrarily set up by arrangement of the base members. Also, by using two or more kind of the air cells from which a size differs, it is possible to set up arbitrarily size of air cells which are provided so as to be disposed in the some flat direction. By this, for example at a hospital, it is possible to change the size or the arrangement of the air cells easily and inexpensively according to the patient's height, body shape, or the state and condition of the affected part. It is exceedingly advantageous for dispersing effectively the pressure added on a patient's body.

Moreover, the air cells are being attached on the base members detachably. By this, when breakage arises on some air cells among the air cells, it is possible to change only the broken air cells. Thus, it is possible to repair the air cells easily and inexpensively.

Also, the air cells are being attached on the base members detachably. By this, it is possible to remove each air cell and to wash each air cell respectively, and it is possible to exchange some air cells for new air cells. By this, for example at a hospital, washing of the air cells becomes easy, and it is possible to exchange some air cells for new air cells according to the state of the air cells. Thus, it is exceedingly advantageous for keeping the air cells clean always.

In order to achieve the above object, in the present invention, a cushion is provide with a plurality of air cells formed to a bag-like shape and being capable of housing air respectively, the air cells having at least one opening portion respectively and having flexibility, a plurality of base members formed board-like shape, a protrusion portion provided on each of base member respectively, the protrusion portion provided on one thickness-direction surface of the base member so as to protrude from one thickness-direction surface of the base member, the protrusion portion having outer surface on which a opening end part of the air cell is detachably attached respectively by fitting, an installation plate having larger area than the base member, a plurality of first connecting portions provided on one thickness-direction surface of the installation plate, a second connecting portion provided on each of the base member respectively, the second connecting portion for detachably attaching the base member to installation plate by connecting with the first connecting portions, a air passage provided on each of the base member respectively, the air passage for sucking/exhausting air in the air cell which is being attached to the base member via the opening portion, and the air passage capable of connecting with the air passage of another base member.

Thus, the base members are detachably attached to the installation plate, and the air cell is detachably attached to each base member respectively. Also, It is possible to attach plural air cell attached base members to the installation plate, and to connect the air passages of the base members each other. By this, it is possible to dispose a plurality of air cells in some flat direction and make the insides of the air cells connect each other.

At this time, arrangement of the air cells can be arbitrarily set up by arrangement of the base members. Also, by using two or more kind of the air cells from which a size differs, it is possible to set up arbitrarily size of air cells which are provided so as to be disposed in the some flat direction. By this, for example at a hospital, it is possible to change the size or the arrangement of the air cells easily and inexpensively according to the patient's height, body shape, or the state and condition of the affected part. It is exceedingly advantageous for dispersing effectively the pressure added on a patient's body.

Moreover, the air cells are being attached on the base members detachably. By this, when breakage arises on some air cells among the air cells, it is possible to change only the broken air cells. Thus, it is possible to repair the air cells easily and inexpensively.

Also, the air cells are being attached on the base members detachably. By this, it is possible to remove each air cell and to wash each air cell respectively, and it is possible to exchange some air cells for new air cells. By this, for example at a hospital, washing of the air cells becomes easy, and it is possible to exchange some air cells for new air cells according to the state of the air cells. Thus, it is exceedingly advantageous for keeping the air cells clean always.

In order to achieve the above object, in the present invention, a cushion is provide with a plurality of air cells formed to a bag-like shape and being capable of housing air respectively, the air cells having at least one opening portion respectively and having flexibility, a plurality of base members formed board-like shape, an installation plate having larger area than the base member, a plurality of through-holes provided on the installation plate so as to penetrate the installation plate in thickness-direction, the through-holes capable of detachably attaching the base members to installation plate respectively by inserting a part of the base member from one thickness-direction surface side to the other thickness-direction surface side of the installation plate and by fitting with said part of the base member, a air passage provided on each of the base member respectively, the air passage for sucking/exhausting air in the air cell which is being attached to the base member via the opening portion, the air passage capable of connecting with the air passage of another base member.

Thus, the base members are detachably attached to the installation plate, and the air cell is detachably attached to each base member respectively. Also, It is possible to attach plural air cell attached base members to the installation plate, and to connect the air passages of the base members each other. By this, it is possible to dispose a plurality of air cells in some flat direction and make the insides of the air cells connect each other.

At this time, arrangement of the air cells can be arbitrarily set up by arrangement of the base members. Also, by using two or more kind of the air cells from which a size differs, it is possible to set up arbitrarily size of air cells which are provided so as to be disposed in the some flat direction. By this, for example at a hospital, it is possible to change the size or the arrangement of the air cells easily and inexpensively according to the patient's height, body shape, or the state and condition of the affected part. It is exceedingly advantageous for dispersing effectively the pressure added on a patient's body.

Moreover, the air cells are being attached on the base members detachably. By this, when breakage arises on some air cells among the air cells, it is possible to change only the broken air cells. Thus, it is possible to repair the air cells easily and inexpensively.

Also, the air cells are being attached on the base members detachably. By this, it is possible to remove each air cell and to wash each air cell respectively, and it is possible to exchange some air cells for new air cells. By this, for example at a hospital, washing of the air cells becomes easy, and it is possible to exchange some air cells for new air cells according to the state of the air cells. Thus, it is exceedingly advantageous for keeping the air cells clean always.

The above and other objects, features, and advantages of the present invention will become more apparent from the following description and the accompanying drawings.

DESCRIPTION OF THE PREFERRED EMBODIMENTS

5

FIGS. 1 to 7 show a first embodiment of the present invention. FIG. 1 is a perspective view of a air cell unit, FIG. 2 is a plan view of the air cell unit, FIG. 3 is a sectional view taken along line A-A in FIG. 1, FIG. 4 is a sectional view taken along line B-B in FIG. 1, FIG. 5 is a perspective view of two air cell units which have not been connected each other, FIG. 6 is a perspective view of the plurality of air cell units connected each other which have not been attached to a installation plate, FIG. 7 is a side sectional view of the plurality of air cell units being attached to the installation plate.

A cushion has a plurality of air cells 10 provided with one opening end portion 11 respectively, a plurality of base members 20 on which the opening end portions 11 of the air cells 10 are being attached respectively, and a plurality of clamp members 30 being attached detachably and respectively to outer surfaces of the air cells 10 being attached to the base members 20. A plurality of air cell units 1 are composed by the air-cells 10, base members 20, and clamp members 30. The cushion also has an installation plate 40 on which the air cell units 1 is attached detachably. The clamp member 30 corresponds to the pressing member indicated in the claims.

The air cell 10 is made from flexible material such as soft rubber material or soft resin material, and the air cell 10 is formed to a bag-like shape and being capable of housing air. The opening end portion 11 is formed so as to be thicker than other portion of the air cell 10. A projection 11a is provided on the inner peripheral surface of the opening end portion 11, and is protruding toward inner side in the radial direction of the air cell 10 compared with the inner peripheral surface of the opening end portion 11.

The base member 20 is made from harder material, such as rubber material or resin material, than the material of the air cell 10, and is formed to a rectangular plate-like shape. A protrusion portion 21 is provided on one thickness-direction surface of the base member 20. The protrusion portion 21 is formed so as to protrude from one thickness-direction surface of the base member 20 and is formed so as to have a circular section shape. A concave portion 22 is provided at the center portion of the protrusion portion 21, and the concave portion 22 is formed so as to extend in the thickness-direction of the base member 20. A radial direction projection 21a is provided on the tip side of the outer peripheral surface of the protrusion portion 21, and the radial direction projection 21a is formed so as to protrude toward outer side of radial direction compared with the outer peripheral surface of the base side of protrusion portion 21. The opening end portion 11 of the air cell 10 is attached to the outer peripheral surface of the protrusion portion 21 by fitting, and the projection 11a of the opening end portion 11 connects with radial projection portion 21a of the protrusion portion 21 in the detachment direction of the air cell 10.

Four air passages 23 are provided in the base member 20 so as to penetrate the base member from outer peripheral surface of the base member 20 to the concave portion 22, the air passages 23 are arranged at equal angle intervals in the circumferential direction each other. The air passages 23 are opening at four end portion of the rectangular base member respectively. Above mentioned opening portions of the air passages 23 consist of cylindrical member 23a respectively.

The cylindrical members 23a are made from rubber material or resin material harder than the material of the base member 20.

One projection portion 24 and one recessed portion 25 are provided on every end portion of the base member 20 respectively. The projection portion 24 and the recessed portion 25 are disposed at a certain position of each end portion of the base member 20. Thus, as shown in FIG. 5, when a plurality of base members 20 are disposed so that their end portions come close to each other, the projection portion 24 of one base member 20 of two close base members 20 and the recessed portion 25 of the other base member 20 of two close base members 20 connect to each other, and the projection portion 24 of the other base member 20 and the recessed portion 25 of one base member 20 connect to each other. By this, if the base member 20 and another base member 20 are disposed on a certain flat surface so that their end portions come close to each other, the base member 20 connects with another base member 20. Thus, the air cells 10 which are attached the base members 20 are disposed in a certain flat direction. When the base members 20 are connected to each other, a plurality of connecting pipes 23b are disposed between base members 20. Also, the connecting pipes 23b are inserted into the cylindrical members 23a of the base members 20. By this, when the base members 20 are connected to each other, the air passages 23 of the base members 20 communicate with each other via the connecting pipes 23b. Four connecting holes 26 are provided in each base member 20, and the connecting holes 26 are formed so as to penetrate the base member 20 in its thickness-direction.

The clamp member 30 is made of coil spring formed into a ring-like shape. After the air cell 10 is attached to the protrusion portion 21 of the base member 20, the clamp member 30 is attached on an outer peripheral surface of the opening end portion 11 of the air cell 10. The clamp member 30 has a smaller inside diameter than an outer diameter of the opening end portion 11 of the air cell 10 being attached to the protrusion portion 21. If the clamp member 30 is attached to the opening end portion 11, the opening end portion 11 is pressed toward the protrusion portion 21 by clamp member 30. In this embodiment, the clamp member 30 is made of coil spring. However, it is possible to employ a ring-like member made from metal material, rubber material or resin material having higher stiffness than the material of the base member 20. In this case, if the ring-like member is formed so that the inside diameter of the ring-like member is slightly smaller than the outer diameter of the opening end portion 11, the opening and portion 11 is pressed toward the protrusion portion 21.

The installation plate 40 is made from rubber material or resin material harder than the material of the air cell 10, and is formed to a rectangular plate-like shape. The installation plate 40 has the area which is larger from several times to several hundred times than the base member 10. A plurality of connecting portions 41 are provided on the upper surface of the installation plate 40, and the connecting portions 41 are formed so as to protrude from the upper surface of the installation plate 40 in the thickness-direction. The connecting portions 41 are formed so that the outer diameter of its tip portion is larger than the outer diameter of its base portion. The connecting portions 41 are disposed on positions which correspond with the positions of the connecting holes 26 of the connected base members 20. The base members 20 are fixed to the installation plate 40 by inserting the connecting portions 41 into the connecting holes 26. The connecting hole 26 engages with the tip portion 41a of the connecting portion 41 being inserted into the connecting hole 26. By this, the resistance force against detachment is generated when the

connecting portions 41 are detached from the connecting holes 26. Thus, the base members 20 are detachably attached to the installation plate 40, and are certainly positioned by the installation plate 40. If the connecting portions 41 are capable of inserting into the connecting holes 26, the base member 20 is capable of being positioned at an arbitrary position on the installation plate 40.

The above-mentioned cushion is used, for example, by being laid on the bed of a hospital, and it has the area according to the size of the bed. Moreover, the cushion laid in the bed is covered with a sheet. The air cells 10 are filled up with the air of predetermined quantity by supplying air from the air passage 23 of at least one base member 20. Thereby, while the patient is lying on the bed, the air pressure in each air cell 10 becomes equivalent to each other by air passages 23 which make the insides of air cells 10 communicate. By this, the pressure added to a patient's body can be dispersed, and generating of a bedsore is prevented.

In this case, by setting up the size and the arrangement of the air cells 10 according to the patient's height, body shape, the state or the condition of the affected part, it is possible to disperse more effectively the pressure added on the patient's body. For example, when the air cell 10 arranged in the position with the tendency for big weight to be added by a patient's shoulder, the waist, and the heel differs from the size of the air cell 10 arranged in other positions, it is possible to disperse more effectively the pressure added on the patient's body. Since the air cells 10 are attached detachably to the base members 20, the size of each air cell 10 and arrangement can be set up arbitrarily.

The air cells 10 are made of soft rubber material or soft resin material in order to disperse the pressure added to the patient's body. For this reason, the air cells 10 are easy to damage. About this situation, the air cells 10 are attached detachably to the base members 20. By this, when breakage arises in some air cells 10, it is possible to exchange only the broken air cell 10.

Furthermore, since each air cell 10 supports the patient through the sheet, it is desirable for each air cell 10 to be always clean. About this situation, the air cells 10 are attached detachably to the base members 20. By this, it is possible to take off each air cell 10 and to wash each air cell 10, it is also possible to exchange some air cells 10 to new air cells.

Moreover, each base member 20 is being fixed to the installation plate 40 respectively. Thereby, a positional deviation of each air cells 10 attached to each base member 20 does not arise easily.

Thus, according to the present embodiment, it is possible to arbitrarily set up the size or the arrangement of the air cells 10. By this, for example, in a hospital, it is possible to exchange the size or the arrangement of the air cells 10 on a bed according to the patient's height, the body shape, state or condition of the affected part. Thus, it is exceedingly advantageous for dispersing effectively the pressure added on the body.

Also, it is possible to change the material, hardness, etc. of the air cells 10 according to the state or the condition of the affected part. For this reason, the pressure added to the body can be distributed more effectively.

Furthermore, when breakage arises in some air cells 10, it is possible to exchange only the air cell 10 which is broken. Thus, it is possible to repair the air cells 10 easily and inexpensively.

Moreover, it is possible to take off each air cell 10 and to wash each air cell 10, it is also possible to exchange some air cells 10 for new air cells 10. By this, for example, in a hospital, it is possible to wash easily the air cells 10, and

exchange the air cells **10** according to state of the air cells **10**. Thus, it is exceedingly advantageous for keeping the air cells **10** always clean.

Also, the protrusion portion **21** is provided on the base member **20**, and the opening end portion **11** of the air cell **10** is attached to the protrusion portion **21** by fitting. Thus, it is possible to attach the air cell **10** to the base member **20** easily and certainly.

Also, the opening end portion **11** which is fitting to the protrusion portion **21** is pressed toward the protrusion portion **21** by the clamp member **30**. By this, it is possible to avoid the air leak from gap between the air cell **10** and the base member **20**, and it is exceedingly advantageous for keeping the constant amount of air in the air cells **10**.

Also, the base members **20** are being fixed on the installation plate **40** respectively, and a positional deviation of each air cells **10** attached to each base member **20** does not arise easily. Thus, it is possible to move the patient on the bed easily.

Moreover, a plurality of connecting portion **41** is provided on the installation plate **40**, and the connecting hole **26** is provided on the base member **20**. Also, by inserting the connecting portions **41** into the connecting hole **26** of each of base member **20**, the base members **20** are detachably fixed on the installation plate **40**. By this, it is possible to change the arrangement of the base members **20**. Thus, when the size or the arrangement of the air cells **10** is changed according to the patient's height, the body shape, or state or condition of the affected part, it is possible to take off the air cells **10** together with base members **20** from installation plate **40**. Therefore, it is exceedingly advantageous for changing the size or the arrangement of the air cells **10** easily and quickly.

In the present embodiment, the cushion is used at bed. However, the cushion is capable of being used at a wheelchair or a chair. At this time, the setup of size and arrangement of the air cells **10** are easy, and exchange and washing of air cells **10** are also easy. Therefore, it is possible to acquire the same effect as the above-mentioned.

Also, in the present embodiment, the base members **20** are fixed on the installation plate **40** respectively. However, Because the base members **20** are capable of connecting each other, without the installation plate **40**, it is also possible to acquire the same effect as the above-mentioned.

Also, in the present embodiment, one opening end portion **11** is provided on each air cell **10** respectively, and the air cell units **1** are composed by attaching one air cell **10** to each base portion material **20** respectively. However, like air cell unit **2** being shown in FIG.8 and FIG. 9, it is possible to provide two opening end portions **51** for each air cell **50** respectively, and to attach two air cells **50** to each base member **52** respectively.

Also, as shown in FIG.10 and FIG. 11, it is possible that the base member **20** to which is attached one air cell **10** connects to the base member **52** to which is attached two air cells **51**. In this case, for example, the base members **20** are disposed on the positions corresponding to the shoulder, the waist, and the heel of the patient to whom weight is added easily. The base members **52** are disposed on other positions. By this, it is possible to effectively disperse the pressure added on the patient's body.

Also, as shown in FIG. 12, by connecting the base members **20**, by connecting air passages **23**, and by closing the air passage which is not connected with another air passage **23**, it is possible to communicate air passages **23** so that the ventilation passageway is formed to the shape shown in FIG. 13. Also, as shown in FIG. 14, it is possible to change the venti-

lation passageway by closing arbitrary air passages **23**. By this, it is possible to adjust the amount of time needed for moving air in air cells **10**.

Also, as shown in FIG. 15, it is possible to provide a base member **60** having air passage **61** which is not connected with the air passage **23** of the base member **20** adjoining to the base member **60**. And, by a connecting pipe **62**, it is possible to communicate air passage **61** of the base member **60** and air passage **23** of the base member **20** which is not adjoining to the base member **60**. Also, it is possible to provide only two air passages **71** on the base member **70**. Thus, By the combination of the base members **20, 60, 70**, it is possible to change the ventilation passageway being formed by air passages **23, 61, 71**.

Moreover, it is possible to arbitrarily change the ventilation passageway being formed by the air passages **23**. To put it concretely, as shown in FIG. 16 and FIG. 17, the air cell units **1** are divided into first to fourth groups **G1, G2, G3, G4** by ventilation passageway being formed by air passages **23**.

Also, opening-and-closing valves **23c** is provided to the air passages **23** connecting first to fourth groups **G1, G2, G3, G4** each other. By the opening-and-closing valve **23c**, it is possible to change the ventilation passageway being formed by the air passages **23**. Thus, by opening all opening-and-closing valves **23c**, air pressure in all the air cell units **1** can be made equivalent. Also, by closing all opening-and-closing valves **23c**, air pressure in air cell units **1** is made equivalent in each group, and it is possible to make difference in air pressure between groups **G1, G2, G3, G4**.

That case where such a cushion is used for a wheelchair is explained below. First of all, at the time someone sit down on it, the opening-and-closing valves **23c** are being opened, and air pressure in the air cells is made equivalent. By this, it is possible to effectively disperse the pressure added on the body. Next, by closing the opening-and-closing valves **23c**, air ventilation between groups is blocked. By this, it is prevented that the air in each air cell **10** moves too much, and it is possible to improve the stability on the cushion.

In the present embodiment, by the clamp member **30**, the opening end portion **11** of the air cell **10** is pressed toward the protrusion portion **21** and being fixed on the protrusion portion **21**. However, as shown in FIG. 18, it is possible to fix the opening end portion **11** of the air cell **10** to the protrusion portion **21** by an adhesive. In this case, the clamp member **30** is unnecessary. Also, it is impossible to exchange only the air cell **10**. But, it is possible to take off the air cell unit **1** which is composed of the air cell **10** and base member **20**. Since the base member **20** is detachably fixed on the installation plate **40**, it is possible to easily carry out the setting up of the size and the arrangement of the air cells **10**, exchange of the air cells **10**, and the washing of the air cells **10**.

In the present embodiment, one air cell **10** is attached on each base member **20** respectively. However, as shown in FIG. 19, it is possible to provide a plurality of protrusion portion **81** to a base member **80**, and attach two or more air cells **10** on the base member **80**.

FIG. 20 to 23 show a second embodiment of the present invention. FIG. 20 is a plan view of a air cell unit, FIG. 21 is a sectional view taken along C-C line in FIG. 20, FIG. 22 is a sectional view showing an essential part of a projection portion and recessed portion, FIG. 23 is a plan view of a cushion. And, it is employed in this embodiment that the same symbols which are being employed to the same or similar structures in the first embodiment.

A cushion has a plurality of air cells **10** and a plurality of clamp members **30** which are same or similar with the first embodiment, a plurality of base members **100** on which the

11

air cells **10** are being attached respectively. And a plurality of air cell units **3** are composed of the air cells **10**, the base members **100**, and the clamp members **30**. Also, the cushion has a pair of first outer frame members **110** and a pair of second outer frame members **111** for covering the outer peripheral portion of the base members **110** being connected, and a dummy member **112**.

The base member **100** is made from rubber material or resin material harder than the material of the air cell **10**, and formed to a hexagon plate-like shape. A protrusion portion **101** is provided on one thickness-direction surface of the base member **100**. The protrusion portion is formed so as to protrude from one thickness-direction surface of the base member **100** and is formed so as to have a circular section shape. A concave portion **102** is provided at the center portion of the protrusion portion **101**, and the concave portion **102** is formed so as to extend in the thickness-direction of the base member **100**. A radial direction projection **101a** is provided on the tip side of the outer peripheral surface of the protrusion portion **101**, and the radial direction projection is formed so as to protrude toward outer side of radial direction compared with the outer peripheral surface of the base side of the protrusion portion **101**. The opening end portion **11** of the air cell **10** is attached to the outer peripheral surface of the protrusion portion **101** by fitting, and the projection **11a** of the opening end portion **11** connects with radial direction projection **101a** of the protrusion portion **101** in the detachment direction of the air cell **10**.

Three projection portions **103** are provided on the outer peripheral surface of the base member **100** and the projection portions **103** are arranged at equal angle intervals in the circumferential direction each other. And three recessed portions **104** are provided on the outer peripheral surface of the base member **100** and the recessed portions **104** are arranged at equal angle intervals in the circumferential direction each other. The recessed portions **104** and the projection portions **103** are alternately disposed in the circumferential direction. The projection portions **103** and the recessed portions **104** are provided on every end portion of the hexagon shaped base member **100** respectively. The outer diameter of the tip portion of the projection portion **103** is larger than the outer diameter of the base side of the projection portion **103**, and the port of the recessed portion **104** is narrower than its inside.

Three air passages **105** are formed in the base member **100** so as to penetrate from the tip portion of each projection portion **103** to the concave portion **102**. Also, three air passages **106** are formed in the base member **100** so as to penetrate from each recessed portion **104** to the concave portion **102**.

Thus, by disposing the base members **100** so as to be adjoined to each other, and fitting projection portions **103** and recessed portions **104** to each other, the base members **100** are connected to each other. By this, the air passages **105** communicate with the air passages **106**.

As shown in FIG. 23, the outer frame members **110**, **111** are formed so as to fit the outer surface of the connected base members **100**. Also, since the outer frame members **110**, **111** are connected to each other, the movement of each base member **100** is restricted.

The dummy member **112** is formed to the same shape with the base member **100** which has a hexagon plate-like shape. The dummy member **112** is disposed at the position which the base member **100** is not being disposed.

Thus, according to the second embodiment, the air cells **10** are detachably attached on the base members **100**. Thus, the setup of size and arrangement of the air cells **10** are easy, and

12

exchange and washing of air cells **10** are also easy. Therefore it is possible to achieve the same effect of the first embodiment.

Also, by connecting the base members **100** to each other, the air passages **105**, **106** are connected to each other. Thus, the setup of size and arrangement of the air cell units **3** becomes easier, and exchange and washing of air cell units **3** becomes easier.

Also, the dummy member **112** is disposed at the position which the base member **100** is not being disposed. By this, it is not necessary to dispose the air cell **10** unnecessarily. Thus, it is possible to effectively dispose the air cells **10**, and prevent the unnecessary breakage of the air cell **10**.

In the second embodiment, two or more base members **100** which have the same size are connected to each other. However, as shown in FIG. 24, it is possible to connect the base member **100** to a base member **120** which has larger size than the base member **100**. In this case, by providing a spacer between the base member **100** and the base member **120**, it is possible to connect without any gap the base member **100** and the base member **120**.

FIG. 25 to 31 show a third embodiment of the present invention. FIG. 25 is a sectional view of a air cell unit, FIG. 26 is a perspective view of a air cell unit, FIG. 27 is a perspective view of a base member, FIG. 28 is a plan view of the base member, FIG. 29 is a perspective view of a cushion at the time when the air cell unit is being attached to an installation plate, FIG. 30 is a perspective view of the cushion at the time when a connecting pipe and a rubber stopper are being attached to air passages, FIG. 31 is a sectional view of the cushion. And, it is employed in this embodiment that the same symbols which are being employed to the same or similar structures in the first embodiment.

A cushion has a plurality of clamp members **30** which are same or similar with the first embodiment, a plurality of air cells **130** having one opening portion respectively, and a plurality of base members **140** on which the air cells **130** are being attached respectively. And a plurality of air cell units **4** are composed of the air cells **130**, the base members **140**, and the clamp members **30**. Also, the cushion has a installation plate **150** on which the base members **140** of the air cell units **4** are being detachably attached.

The air cell **130** is made from flexible material such as soft rubber material or soft resin material, and the air cell **130** is formed to a bag-like shape and being capable of housing air. The opening end portion **131** is formed so as to be thicker than other portion of the air cell **130**. Also, the inner peripheral surface of the opening end portion **131** is protruding inner side compared with the other portion of the inner peripheral surface of the air cell **130**.

The base member **140** is made from harder material, such as rubber material or resin material, than the material of the air cell **130**, and is formed to a circular plate-like shape. A first protrusion portion **141** is provided on one thickness-direction surface of the base member **140**. The first protrusion portion is formed so as to protrude from one thickness-direction surface of the base member **140** and is formed so as to have a circular section shape. A concave portion **142** is provided at the center portion of the first protrusion portion **141**, and the concave portion **142** is formed so as to extend in the thickness-direction of the base member **140**. A radial direction projection **141a** is provided on the tip side of the outer peripheral surface of the protrusion portion **141**, and the radial direction projection **141a** is formed so as to protrude toward

outer side of radial direction compared with the outer peripheral surface of the base side of the first protrusion portion **141**. The opening end portion **131** of the air cell **130** is attached to

13

the outer peripheral surface of the first protrusion portion 141 by fitting, and the inner peripheral surface of the opening end portion 131 connects with radial projection portion 141a of the first protrusion portion 141 in the detachment direction of the air cell 130. After the air cell 130 is attached to the first protrusion portion 141 of the base member 140, the clamp member 30 is attached on outer peripheral surface of the opening end portion 131 of the air cell 130. By this, the opening end portion 131 is pressed toward the first protrusion portion 141 by clamp member 30.

A second protrusion portion 143 is provided on the other thickness-direction surface of the base member 140. The second protrusion portion is formed so as to protrude from the other thickness-direction surface of the base member 140 and is formed so as to have a circular section shape. Four air passages 144 are provided in the second protrusion portion 143 so as to penetrate the second protrusion portion 143 from outer peripheral surface of the second protrusion portion 143 to the concave portion 142. Also, the air passages 144 are arranged at equal angle intervals in the circumferential direction each other.

The installation plate 150 is made from rubber material or resin material harder than the material of the air cell 130, and is formed to a rectangular plate-like shape. The installation plate 150 has the area which is larger from several times to several hundred times than the base member 140. A plurality of through-holes are provided on the installation plate 150 so as to penetrate the installation plate 150 in thickness-direction. The inside diameter of the through-hole 151 is slightly smaller than the outer diameter of the second protrusion portion of the base member 140. If the second protrusion portions 143 are respectively inserted into each through-hole 151 from one thickness-direction surface side to the other thickness-direction surface side of the installation plate 150, the second protrusion portions 143 of the base members 140 are fitted to each through-hole 151. By this, the base members 140 are detachably attached to the installation plate 150. Also, the other thickness-direction surface of the base member meets the one thickness-direction surface of the installation plate 150. By this, the base members 140 are disposed so as to be arranged on a certain flat surface. When the base members 140 are attached to the installation plate 150, the second protrusion portion 143 of the base member 140 sticks out from the other thickness-direction surface of the installation plate 150. Also, the air passages 144 provided in the second protrusion portion 143 are disposed at the other thickness-direction surface side of the installation plate 150. In this case, a plurality of connecting pipes 160 are disposed between the base members 140, and the connecting pipe 160 are inserted into the air passages 144 respectively. By this, the air passages 144 of the base members 140 communicate each other via the connecting pipes 160. The connecting pipe 160 corresponds to the connecting member written in the claims. The air passage 144 into which the connecting pipe 40 is not inserted is closed by the rubber stopper 161. In the present embodiment, the air passage 144 into which the connecting pipe 40 is not inserted is closed by the rubber stopper. However, it is possible to form the air passages 144 by only the necessary number for inserting the connecting pipes 160. For example, four base members 140 disposed at each of the four corners of the cushion are provided with two air passages 144 respectively. By this, it is possible to save the time and effort to close the air passage 144 with the rubber plug 161.

The above-mentioned cushion is used in the state it is being placed on the seating portion of a wheelchair. Also, the cushion has the area corresponding to the seating portion. The air cells 140 are filled with a certain amount of air. By this, if

14

someone sit down on the wheelchair, the air pressures in the air cells 130 become equal level each other. Thus, by dispersing the pressure added to the sitting person's body, it is possible to prevent the generating of bedsores.

In this case, by setting up the size or the arrangement of the air cells 130 according to the sitting person's body shape, it is possible to disperse more effectively the pressure added to the sitting person's body. For example, if the size of the air cells 130 for supporting the buttocks and its neighborhood of the sitting person is different from the size of the air cells 130 disposed on the other position, it is possible to effectively reduce the pressure added to the sitting person's body. Since the air cells 130 are detachably attached on each base member 140, it is possible to arbitrarily set up the size or arrangement of the air cells 130.

The air cells 130 are made from soft rubber material or soft resin material for dispersing the pressure added to the sitting person's body. By this, the air cells 130 are easy to damage. About this situation, the air cells 130 are detachably attached on the base members 140. Thus, if the some air cells 130 are broken, it is possible to exchange only the broken air cells 130.

Moreover, since the air cells support the sitting person, it is desirable to always keep the air cells 130 in a clean state. About this situation, the air cells 130 are detachably attached on the base members 140. Thus, it is possible to take off and wash each air cell 130 respectively, and exchange some air cells 130 for new air cells 130.

The base members 140 are attached to the installation plate 150 respectively. Thereby, a positional deviation of each of the air cells 130 attached to each base member 140 does not arise easily.

Thus, according to the present embodiment, it is possible to arbitrarily set up the size or the arrangement of the air cells 130. Thus, it is possible to change the size or the arrangement of the air cells 130 on the wheelchair according to the sitting person's shape. Also, it is exceedingly advantageous for effectively dispersing the pressure added to the body.

Also, it is possible to arbitrarily change the material, hardness, etc. of the air cells 130. For this reason, the pressure added to the body can be distributed more effectively.

Furthermore, when some air cells 130 are broken, it is possible to exchange only the broken air cells 130. By this, it is possible to repair the air cells 130 easily and inexpensively.

Moreover, it is possible to take off each air cell 130 and to wash each air cell 130, it is also possible to exchange some air cells 130 for new air cells 130. By this, it is possible to easily wash the air cells 130, and exchange the air cells 130 according to the state of the air cells 130. Thus, it is exceedingly advantageous for always keeping the air cells 130 clean.

Also, a plurality of through-holes 151 are provided on the installation plate 150 so as to penetrate the installation plate 150 in the thickness-direction of the installation plate 150. When the second protrusion portions 143 of the base members 140 are inserted into the through holes 151 from one thickness-direction surface side to the other thickness-direction surface side of the installation plate 150 respectively, the base members 140 are attached to the installation plate 150. By this, it is possible to attach the base members 140 to the installation plate 150 easily and certainly, and the base members 140 can be attached and detached in a short time.

Also, the second protrusion portions 143 of the base members 140 project from the other thickness-direction surface of the installation plate 150. Moreover, the air passages 144 of the base members 140 are disposed at the other thickness-direction surface side of the installation plate 150, and the air passages 144 communicate with each other by the connecting

15

pipes 160. By this, even when the air cells 130 are being disposed so as to be adjacent each other, the air passages 144 can be connected to each other easily and certainly. Thus, it is exceedingly advantageous for reducing work hours of connecting the air passages 144. If the air passages 144 and the connecting pipes 160 are disposed at the other thickness-direction surface side of the installation plate 150, there is the chance that deformation of the air cells 130 is restricted by the air passages 144 and the connecting pipes 160. However, in the present embodiment, since deformation of the air cells 130 is not restricted by the air passages 144 and the connecting pipes 160, it is exceedingly advantageous for dispersing the pressure added to the body. Furthermore, the ventilation passageway formed by connecting the air passages 144 by the connecting pipes 160 is not restricted by the air cells 130. Thus, it is advantageous for arbitrarily changing the ventilation passageway formed by connecting the air passages 144.

In the present embodiment, the installation plate 150 is formed in a uniform thickness size. However, it is possible to form a part of the installation plate 150 so as to be different in thickness compared with the other part of the installation plate 150. Also, it is possible to provide the base members 170, 171 according to the thickness of the installation plate 150, and provide the air cells 180, 181 according to the base members 170, 171 respectively. By this, the base members 130, 170, 171 are disposed so as to be arranged on a certain surface. Also, the air cells 130, 180, 181 are formed so that the top of the air cells 130, 180, 181 are positioned at the same height each other. By this, if the installation plate 150 is formed so that the thickness volume of the portion corresponding to the air cells 130 disposed near buttock is smaller than the thickness volume of the other portion, the air cells 130 disposed near buttock become higher. It is possible to reduce effectively the pressure added to the buttock that tends to become more high pressure than the other portion. It is possible to reduce effectively the pressure added to the buttock that tends to become higher pressure than the other portion. Thus, it is possible to disperse more effectively the pressure added to the body.

The preferred embodiments described in this specification are illustrative and not restrictive. The scope of invention is given by the appended claims, and all changes and modifications included in the meaning of claims are embraced in the present invention.

What is claimed is:

1. An air cell unit, comprising:
an air cell being capable of housing air, the air cell having at least one opening portion and having flexibility;
a base member defined by two thickness-direction surfaces connected to each other by an outer peripheral surface;
a protrusion portion provided on one of said thickness-direction surfaces of the base member so as to protrude from the one thickness-direction surface of the base member in the thickness direction, the protrusion portion having an outer surface on which an opening end part of the air cell is detachably attached by a fitting such that said opening end part of the air cell surrounds the protrusion portion;
at least one of a projection portion or a recessed portion provided on said outer peripheral surface of said base member and being protruded or recessed in the direction perpendicular to the thickness direction of the base member, wherein the projection portion extends laterally beyond said base member, the projection portion or the recessed portion for connecting the base member and another base member by being formed so as to connect with the other of a projection portion or a recessed portion

16

tion of another base member when the base member and another base member are disposed on a flat direction so that their end portions in the direction perpendicular to the thickness direction are adjacent to each other;

5 an air passage provided in the base member, the air passage communicating air in the air cell that is attached to the base member via the opening portion, the air passage being capable of connecting with an air passage of another base member; and

a pressing member for pressing the opening end part of the air cell toward the protrusion portion in a state in which the opening end part of the air cell is attached to the protrusion portion.

2. The air cell unit according to claim 1, wherein the air passage is formed so as to connect with the air passage of another base member by connecting the base member to another base member.

3. The air cell unit according to claim 1, wherein said pressing member is a generally annular member.

4. The air cell unit according to claim 1, wherein said base member is board-shaped.

5. The air cell unit according to claim 1, wherein said pressing member is a separate member that surrounds both the opening end part and the protrusion portion.

6. The air cell unit according to claim 1, wherein each of said base members includes both a projection portion and a recessed portion.

7. The air cell unit according to claim 6, wherein said projection portion and said recessed portion are located on opposite sides of said outer peripheral surface of said base member.

35 8. The air cell unit according to claim 6, wherein said projection portion and said recessed portion are located on the same side of said outer peripheral surface of said base member, such that said projection portion and said recessed portion are adjacent each other.

9. A cushion, comprising:
a plurality of air cells being capable of housing air, the air cells each having at least one opening portion and each having flexibility;

a plurality of base members each defined by two thickness-direction surfaces connected to each other by an outer peripheral surface;

a protrusion portion provided on each of the base members, the protrusion portion provided on one of said thickness-direction surfaces of the base member so as to protrude from the one thickness-direction surface of the base member in the thickness direction, the protrusion portion having an outer surface onto which an opening end part of the air cell is detachably attached by a fitting such that said opening end part of the air cell surrounds the protrusion portion, wherein said opening end part is integrally formed with the air cell, and is formed of the same flexible material as the air cell;

an installation plate having a larger area than the base member;

a plurality of first connecting portions provided on one thickness-direction surface of the installation plate;

a second connecting portion provided on each of the base members, the second connecting portions for detachably attaching the base members to the installation plate by connecting with the first connecting portions;

at least one of a projection portion or a recessed portion provided on said outer peripheral surface of said base member and being protruded or recessed in the direction perpendicular to the thickness direction of the base member, wherein the projection portion extends laterally beyond the base member.

ally beyond said base member, the projection portion or the recessed portion for connecting the base member and another base member by being formed so as to connect with the other of a projection portion or a recessed portion of another base member when the base member and another base member are disposed on a flat direction so that their end portions in the direction perpendicular to the thickness direction are adjacent to each other; an air passage provided in each of the base members, the air passage for communicating air to/from the air cell which is attached to the base member via the opening portion, the air passage being capable of connecting with the air passage of another base member; and a pressing member for pressing the opening end part of the air cell radially inwardly toward the protrusion portion in a state in which the opening end part of the air cell is attached to the protrusion portion, wherein said pressing member is a separate member that surrounds both the opening end part and the protrusion portion.
